Primary Examiner — Leanne Was-Englehart*Assistant Examiner* — Molly Loch(74) *Attorney, Agent, or Firm* — Blank Rome LLP(57) **CLAIM**

The ornamental design for a watch dial as shown and described.

DESCRIPTION

FIG. 1 is a top view of a watch dial of my present design; FIG. 2 is a bottom view thereof; FIG. 3 is a right side view thereof; FIG. 4 is a left side view thereof; FIG. 5 is a front view thereof; FIG. 6 is a rear view thereof; and FIG. 7 is a top right perspective view thereof; and, FIG. 8 is a bottom left perspective view thereof.

The broken lines illustrate portions of the dial that form no part of the claimed design.

The surface hatching shown in FIGS. 1 and 7 is intended delineate surface character and contour rather than a surface content or pattern.
